UNITED STATES PATENT OFFICE

1,921,503

DRILLING APPARATUS

John M. Calderwood, Salt Lake City, Utah

Application September 22, 1928
Serial No. 307,582

2 Claims. (Cl. 255—41)

My invention relates to drill holders or rock drilling apparatus and has for its object to provide a new and efficient means for sliding, tilting, retracting, and projecting the drill steel in the 5 operation of the device, and to automatically move or throw back the drillings or cuttings from the point of the bit and at the same time to permit the drill steel to turn freely while the bit is drawn back.

10 A further object is to provide means by which the outrigger arm may be lengthened or shortened in order to expedite the adjustment from one position to another, enabling the operator to greatly facilitate the work and materially increase the footage covered per day.

This invention is an improvement on the drill holders set forth in the Letters Patent issued to me on July 23, 1918, Number 1,273,733, and March 11, 1919, Number 1,298,918, with additional modifications not embodied in either of said Letters Patent.

In the drawings, in which I have shown the preferred manner of building my invention Figure 1 is a side elevation of the device. Figure 2 is a plan view of the mounting portion of my device showing the pivoting thereof. Figure 3 is a side view of the pivot bearing in which the tilting head is carried and supported. Figure 4 is a modification of my invention showing the 30 use of a ratchet to turn the drill instead of by gearing. Figure 5 is a side elevation of the drill supporting and turning apparatus. Figure 6 is an end view of the levers for projecting and retracting the drill. Figure 7 is an end view of 35 one of the clamps used to hold the drill from turning.

In the drawings, the column upon which my device is carried is shown at A, with a collar B secured on the said column by suitable set screws. 40 Above the collar B and encircling the column A, I provide a sleeve 3, which sleeve is provided with a bearing clamp 4 on one side thereof in which a stub shaft 4a is carried. The stub shaft 4a is formed on a socket 5, which socket is adapted 45 to hold a support bar 9, and the shaft 4a acts as the pivot for the bar 9. Another socket 6 is carried on the bar 9 and has a bearing clamp 7 formed on the top side thereof, in which the stub shaft 8 of a tiltable head 10 is carried. This 50 is the pivot for the tiltable head 10 to adapt the machine to bore at any desired angle. The sleeve 3 is the horizontal pivot for the entire operating portion of the device. Longitudinally and adjustably carried on the said support bar 9, is 55 a tiltable head 10 which head 10 is the main body

and support member of the machine. A bolt 13 is provided to tighten the bearing clamp 7 on the stub shaft 8. This construction provides a pivot point for the drill carrying framework C, on which the drill is carried and to which the hammer is secured, and also provides an easy method of changing the angle of the drill. Depending from the tiltable head 10 I provide a drill carrying framework C which framework is made up of an upright member C1 secured to the head 60 10 and an angle brace C2 which is secured at its lower end to the member C1 and at its upper end to the head 10. Cross members 19 and 20 are provided on the framework and the extreme ends thereof are pivot points for the retracting 65 70 and projecting levers 21 and 22. The lever 21 has slots 21a and 21b in the ends thereof in which slots the pivot pins operate when the lever is moved by the movement of the hammer handle. The said levers 21 and 22 are pivoted to the members 19 and 20 by suitable pins and are each secured together by the pivot pin 22a. The lever 22 is made up of two bars 11 and 12 which are spaced apart by the screw tightener 13a and the lower ends 14 of the bars are bent inwardly to 75 80 partially encircle a flanged drill holding socket 15. A spring 16 holds the bars apart when the screw tightener 13a is released. A rack 17 is slidably carried in the framework C through a bracket D on the angle braces C1 and C2, and the inner end of the said rack is secured to an adjustable member 17a which in turn is secured to 85 a handle clamp 18, which handle clamp is secured on the handle F of my hammer. The said lever 21 is secured to the said rack at the point at 90 which the rack and the member 17a are pivoted together.

On the lower end of the framework C, is a bifurcated bearing 40 which carries a rotatable member 41, therein. The said rotatable member 95 41 is provided with a medially situated ring gear 42, and the said member 41 is provided with a hexagonal central hole 43 therethrough, through which the drill bit G is placed, carried and operated. A drive shaft 44 is mounted in a suitable bearing 44a on the bearing 40 and a pinion 45 100 is mounted on the lower end with the teeth of the pinion 45 meshing with the teeth of the gear 42. The upper end of the said shaft 44 is mounted in a bearing in the head 10 and a pinion gear 47 105 is carried on the said shaft with the teeth thereof meshing with the teeth on the rack 17, so that when the rack 17 is moved longitudinally by the movement of the hammer handle the pinion will 110 rotate the shaft 44 and the gear 42 and will ro-

tate the member 41 thereby rotating the drill bit. The pinion 47 is provided with a ratchet 48 on the lower side thereof so that only the backwardly movement of the rack 17 will rotate the pinion and a spring 48a holds the pinion 47 in engagement with said ratchet 48. The lower end of the lever 22 is engaged with the drill holding socket 15, through which the drill bit G is placed and a bolt 24 in the clamp 23, which is a portion 10 of the socket 15, secures the bit securely therein so that when the lever is moved by the action of the hammer handle the bit will be moved forwardly on the forward stroke of the hammer and backwardly as the motion of the handle moves 15 in the opposite directions. The socket 15 is made so that the bit G may not rotate therein, but the socket will rotate in between the ends 14 of the bars 11 and 12 without undue friction, but so that it will move the bit forward and back with 20 every movement of the hammer handle.

The said hammer handle F is pivoted at its upper end by the pin 49 in the block 26, and the front end of the block 26 is provided with a bar 23a which bar is carried in a socket in the head 25 10 and a set screw 28 is secured in the head 10 to secure the said bar 23a in any desired position. With this construction the pivoted end of the hammer handle F may be moved forwardly or backwardly from the work as the bit is moved 20 to or away from the work, the set screw 28 may be loosened and the hammer handle set nearer to the work. This also provides for different length bits to be used in my device without unnecessary changes in the machine. A hammer head F1 is secured on the lower free end of the handle F and is adapted to be moved backwardly and forwardly to hit the end of the drill bit G. A control lever 25 is secured to the block 26 and an adjustable spring clamp 29 is carried 25 40 thereon with means for securing the hook to the handle at any desired position by set screws 30. A spring clamp 32 provided with hooks on each side thereof is then secured to the hammer handle F in which the ends of springs 31 and 31a are carried. The other end of the spring 31 is secured to the spring clamp 29 and the other end of the spring 31a is secured to another spring clamp 35. The said spring clamp 35 is secured to a rod 36 mounted on the upright member C1 of the framework C. These springs so secured assist the hammer in its work and assist the operator to withdraw and force the hammer to and from the end of the drill bit with more force and greater speed than he normally could exert.

The operation of my device is as follows:—

The column is set in the desired place and the drill directed into the spot in which the hole is required. The bearing clamp 7 is then tightened 60 65 securing the device in the angled position, and the sleeve 3 is tightened around the column securing the direction of the bit. The operator may then commence to drill. With either hand

he may grasp the handle of the hammer F and move the head F1 to and from the bit with any desired force. The springs 31 and 31a will aid him in his operation and in cases where the drill is inclined upwardly both springs can be attached to the same side of the hammer to help in the drilling, or vice versa where the bit is inclined downwardly. When the drill hammer is withdrawn the levers 21 and 22 will be operated and the drill bit withdrawn from the hole a short distance and as the hammer moves in the opposite direction the bit will be moved into the hole until when the hammer hits the end of the bit it will be against the inner face of the hole. With each backward motion of the hammer handle the rack 17 will rotate the shaft by the pinion 47, and the gear 42 will be rotated by the pinion 45 which will rotate the member 41 rotating the drill with each hammer blow. As the handle is advanced the ratchet under the pinion 47 will allow the pinion to rotate without rotating the shaft.

Having thus described my invention I desire to secure by Letters Patent and claim:

1. In a device of the class described the combination of a drill supporting framework having a drill carrying bearing suspended therefrom; a drill passed therethrough; clamps to hold the drill from turning in a rotatable member, said member being carried in said framework bearing; a ring gear formed around said member; a hammer suspended from said framework; means connected with said hammer to rotate said rotatable member with each stroke of the hammer; a drill holding socket carried on the drill backwardly of the rotatable member; a lever, pivotally supported from said framework, having one end clamped to said socket; another lever secured to the free end of the first mentioned lever and also supported from said framework, said second lever actuated by the movement of the hammer handle; springs attached to the handle and framework to aid in actuating said hammer; and a column to which the entire framework is pivotally secured.

2. In a device of the class described the combination of a drill support column; a framework secured adjustably thereto; a hammer pivotally suspended from said framework; a bearing suspended from said framework; a rotatable member carried in said bearing; a drill carried in said rotatable member; means to rotate the rotatable member and said drill; a drill holding clamp secured on said drill; a lever pivoted to said framework and secured to said clamp; another lever pivotally jointed to the top end of the first lever and also pivoted to said framework; a link pivotally connecting said last lever with the hammer handle to move said clamp and drill forwardly and backwardly by each forward and backward movement of the hammer handle.

JOHN M. CALDERWOOD.
